NAIL HOLDER

Filed Feb. 28, 1929

INVENTOR.

Oscar Breithaupt

BY

Thomas Donnelly
ATTORNEY.

UNITED STATES PATENT OFFICE

OSCAR BREITHAUPT, OF DETROIT, MICHIGAN.

NAIL HOLDER

Application filed February 28, 1929. Serial No. 345,296.

My invention relates to a new and useful improvement in a nail holder particularly adapted for use with small nails and tacks.

It is an object of the present invention to provide a nail holder which will have a trough through which the nails may be fed to a retaining member from which they are used, so constructed and arranged as to permit the use of the holder with small nails or tacks.

Another object of the invention is the provision in a nail holder of this class of a swingably mounted supporting or retaining member.

Another object of the invention is the provision of means for agitating the nails or tacks so that they may be readily fed.

Another object of the invention is the provision of an inclined retaining or supporting member curved intermediate its ends.

Another object of the invention is the provision of a retaining or supporting member so arranged and shaped as to assure the supporting of the nails or tacks in upright position.

Another object of the invention is the provision of a separating member so arranged as to direct the nails or tacks into the proper position for being supported or retained prior to use.

Other objects will appear hereinafter.

The invention consists in the combination and arrangement of parts hereinafter described and claimed.

The invention will be best understood from a reference to the accompanying drawings which form a part of this specification and in which,

Fig. 1 is a side elevational view of the invention with parts broken away and parts shown in section.

Fig. 2 is a fragmentary top plan view of the invention.

Fig. 3 is a sectional view taken on line 3-3 of Fig. 1.

Fig. 4 is a sectional view taken on line 4-4 of Fig. 2.

Fig. 5 is a fragmentary perspective view of the track member.

Fig. 6 is a fragmentary side elevational view of a modified form of the invention.

Fig. 7 is a fragmentary top plan view of the modified form of the invention.

Fig. 8 is a fragmentary view taken on line 8-8 of Fig. 7.

Fig. 9 is a sectional view taken on line 9-9 of Fig. 7.

The invention, as shown in the drawings, comprises a hopper or nail container 7 to which is secured a suitable band 8 whereby the device may be mounted on the head of the user. Formed in the bottom 9 of the container or hopper 7 is an opening 10 positioned at the rear of the base and communicating with a forward directed downwardly inclined trough 11 having an angularly turned and normally horizontally disposed end portion 12, the base 13 of which is turned upwardly at its end as at 14. An outlet opening 15 is formed in the rear of the base portion 13 and adapted to deposit tacks and short nails into the trough 16 which is positioned therebelow. Extending longitudinally of and centrally in the trough 16 is a separating member or rib 17 which serves to divide the trough 16 into a pair of compartments 18 and 19, these compartments being wider between the top and bottom thereof than at the top and bottom. It will be noted that the side walls of the trough 16 terminate adjacent the enlarged lower end of the rib 17 to provide outlet slots 18' and 19'. Mounted on the horizontally disposed portion 12 and angularly turned so as to extend downwardly therefrom is a spring arm 20 which projects between the rib 17 and the inclined strap 21 which is secured to or projected outwardly from the trough 16. This strap 21 is curved as at 23 and the extension 24 of the rib 17 is also curved.

A similar strap 26 is mounted at the opposite side of the rib 17 and similarly curved as at 27, these straps being connected at their ends by the cross bar 25. As shown in Fig. 5, the extension 24 of the rib 17 is formed wider at its base than at its top and there is a slot 28 between the strap 26 and this extension 24 and a slot 29 between the extension 24 and the strap 21. The upper face

95
100

of the extension 24 is formed concave as at 24'. A similar spring arm 30 projects downwardly between the strap 26 and the rib 17. A leaf spring 31 serves to mount the trough 16 on the trough 11.

In use, the nails or tacks are deposited in the hopper 7 and the bottom 9 thereof is normally inclined downwardly so that the opening 10 is at the elevated ends of the bottom. By shaking the head, the nails and tacks are precipitated through the opening 10 and permitted to slide down the trough 11 so as to be deposited through the opening 15 into either the compartment 18 or the compartment 19. By forming these compartments bulged outwardly adjacent their center as clearly appears in Fig. 3, a proper arrangement of the nails or tacks so that they may project with their pointed ends extending through the slots 18' and 19' is made possible. The spring arms 20 and 30 serve to prevent passage of the tacks or nails from the trough 16 unless and until they have engaged in the slots 29 and 28 so that they may slide forward in proper position for being lifted from the retainer by means of a magnetic hammer or the like. Furthermore, the concave face 24' assists in preventing a disarrangement of the tacks so that a proper feeding of the same may be effected at all times. As the hammer is placed upon the retainer to remove a tack therefrom, the trough 16 will be swung downwardly against the tension of the spring 31 and when this downward pressure is relieved, this trough 16 will spring back into its normal position, thus agitating the tacks and nails and assuring a proper feeding of the same through the opening 15 and a proper arrangement of the tacks and short nails in the compartments 18 and 19.

In the modified form, I have shown a trough 11' with an extension formed from a single sheet of metal and having the outwardly curved side edges 31' and 38. The strap 33 is provided with the elongated slot 36 through which the tacks or nails may be projected so as to hang by their heads and this strap 33 is curved as at 34 and 35 to prevent undue feeding of the tacks or nails along the same. To prevent too rapid passage of the tacks or nails onto the member 33, I have provided a spring arm 37 which is mounted on the trough 11' and extended angularly at its free end across the slot 36 so as to engage the ends of the tacks or nails slightly.

By having the trough curved as shown in the preferred form, the nails or tacks are always retained in a position clearly visible to the user so that ready and quick removal of the tacks or nails therefrom may be accomplished.

While I have illustrated and described the preferred form of my invention, I do not wish to limit myself to the precise detail of

structure shown but desire to avail myself of such variations and modifications as come within the scope of the appended claims.

Having thus described my invention, what I claim as new and desire to secure by Letters Patent is:

1. A nail holder of the class described comprising: a nail receiving hopper; a conveying trough positioned beneath and inclined downwardly and outwardly from said hopper, the lower end of said trough being angularly turned and provided with an opening therein; a nail receiving trough positioned beneath said opening; a spring arm for connecting said last mentioned trough to the inclined portion of said first mentioned trough; and a resilient member mounted on the angularly turned portion of said first mentioned trough and projected downwardly to said second mentioned trough.

2. A nail holder of the class described comprising: a nail receiving hopper; a conveying trough positioned beneath and inclined downwardly and outwardly from said hopper, the lower end of said trough being angularly turned and provided with an opening therein; a nail receiving trough positioned beneath said opening; a spring arm for connecting said last mentioned trough to the inclined portion of said first mentioned trough; and a nail supporting portion projecting outwardly from said second mentioned trough.

3. A nail holder of the class described comprising: a nail receiving hopper; a conveying trough positioned beneath and inclined downwardly and outwardly from said hopper, the lower end of said trough being angularly turned and provided with an opening therein; a nail receiving trough positioned beneath said opening; a spring arm for connecting said last mentioned trough to the inclined portion of said first mentioned trough; a separating member positioned in said second mentioned trough and dividing said trough into a pair of compartments, said compartments being wider generally than at the top of base.

In testimony whereof I have signed the foregoing specification.

OSCAR BREITHAUPt.
